UNITED STATES PATENT OFFICE.

JOHN FOLK, OF NEW YORK, N. Y., ASSIGNOR TO UNITED TEXTILE PRINT WORKS, INC., OF NEW YORK, N. Y., A CORPORATION OF NEW YORK.

DESIGN FOR A TEXTILE FABRIC.

Application filed April 10, 1924. Serial No. 9,216. Term of patent 3½ years.

To all whom it may concern:

Be it known that I, JOHN FOLK, a citizen of Hungary, and resident of the borough of Manhattan, city of New York, in the county of New York and State of New York, have invented a new, original, and ornamental Design for Textile Fabric, of which the following is a specification, reference being had to the accompanying drawing, forming part thereof.

The figure is a face view of a piece of textile fabric showing my new design.

I claim:

The ornamental design for a textile fabric as shown.

Signed at the borough of Manhattan, city of New York, in the county of New York and State of New York, this 5th day of April, A. D. 1924.

JOHN FOLK.
